Kevin Prince(57) **CLAIM**

The ornamental design for a tamper-evident container, as shown and described.

DESCRIPTION

FIG. 1 is a perspective view of a tamper-evident container, showing my new design in a closed and locked position; FIG. 2 is a perspective view thereof, illustrated in an unlocked and slightly open position; FIG. 3 is a front elevational view of FIG. 1; FIG. 4 is a rear elevational view of FIG. 1; FIG. 5 is a top plan view of FIG. 1; FIG. 6 is a bottom plan view of FIG. 1; FIG. 7 is a left-side elevational view of FIG. 1, the right-side elevational view being a mirror image thereof; and, FIG. 8 is a top plan view of the container of FIG. 1, illustrated in an unassembled, flat blank configuration. The broken lines showing a box fastener in FIGS. 1 and 2 depict environmental matter and form no part of the claimed design. The U-shaped broken lines on the top panel of the container and the I-shaped broken lines on the front of the container represent perforations, and do form part of the claimed design.
